UNITED STATES PATENT OFFICE

MARIAN RAY, OF TAMPA, FLORIDA, ASSIGNOR TO SIDNEY BLUMENTHAL & CO. INC., OF NEW YORK, N. Y., A CORPORATION OF NEW YORK

WEARING APPAREL

Application filed May 29, 1931. Serial No. 540,955.

This invention relates to improvements in wearing apparel and more particularly to the skirt portion of an ensemble.

One object of my invention is to provide a skirt which is adapted to easily and readily be changed to conform to conventional custom or requirement, as, for instance, changing the length of the skirt from an ankle length to a knee length, at the same time reducing 10 the width of the skirt accordingly.

Another object is to provide a skirt which is adjustable to accommodate different sizes of waists and hips, so as to conform to various figures.

15 Another object is to provide a skirt which is formed substantially of one piece of material and is arranged to be wrapped around the figure of the wearer and securely fastened in position thereon.

20 Another object is to provide certain improvements in the form, construction and arrangement of the several parts whereby the above named and other objects may effectively be attained.

25 A practical embodiment of my invention is represented in the accompanying drawings, in which

Fig. 1 represents a front elevation of my improved skirt, showing the position it assumes when worn as an ankle length skirt.

Fig. 2 represents a similar view with the skirt shown in the position it assumes when worn as a knee length skirt.

Fig. 3 represents a detail vertical section, 35 on a larger scale, taken in the plane of the line III—III of Fig. 1, looking in the direction of the arrows.

Fig. 4 represents a similar view taken in the plane of the line IV—IV of Fig. 2, looking in the direction of the arrows, and

Fig. 5 represents a view of the skirt in its unwrapped position on a scale similar to Figs. 1 and 2.

In conformity with the present conventional custom and in the light of economy, 45 it is desirous that my improved skirt serves a two-fold purpose, namely, a long, loose, full fashioned skirt for evening wear or dress occasions, and a short, form-fitting skirt of a length suitable for walking or sport wear.

The skirt may be formed substantially of one piece of material and is applied to the figure of the wearer by being wrapped around, so that one side overlaps the opposite side.

In the drawings the garment represented 55 comprises a yoke 1 of relatively light material, such as silk or other similar fabric, and a skirt portion 2 formed of textile material suitable for dress or other occasions. The yoke consists of three separable sections and 60 are designated by a back section 3 and two smaller front sections 4, 5.

The skirt portion 2, in the present instance, 65 is formed of three gores and is designated by a back gore 6 and two front gores 7, 8, which are permanently joined to the back gore 6 along the vertical edges 9, 10, respectively. The back section 3 of the yoke is stitched to the upper edge of the gore 6 at 11, while the front sections 4, 5 are similarly secured to the top edges of the front gores 7, 8 at 12, 13, respectively.

The vertical edges 14, 15 of the front sections 4, 5 of the yoke are removably connected to the adjacent vertical edges 16, 17 of the back gore 6 by means of hooks and eyes 18 or other suitable fastening means. To secure the yoke around the body of the wearer 70 at the waistline, I provide a series of fastening means, such as snap fasteners, one member 19 of each of which is attached along the upper edge of the front section 4 of the yoke, while the other coating member 20 is secured to the upper edge of the other front section 5 of the yoke. These fastening 75 members are disposed along the upper edges of the front sections 4, 5 at regular intervals and thereby provide a uniform adjustment 80 of the yoke to the body of the wearer.

Similar fastening means 21, 22 are fixed to the upper edges of the front gores of the skirt portion 2 adjacent the lower edges of the front sections 4, 5 of the yoke 1 and at 85 regular intervals, which means connect the front gores 7, 8 at the hip portion of the wearer and tend to wrap the gore 8 slightly over the gore 7 and snugly around the hips of the wearer, so that the bottom of the gores will flare outwardly a slight distance 90 100

and hang therefrom in graceful folds, as desired in conjunction with other garments to be worn on dress occasions. In this position the garment has a full length skirt having the desired width for style.

5 When it is desired to shorten the length of the skirt, the sections of the yoke are left unhooked and the back section 3 and front section 4 folded along lines 11, 12 inwardly 10 to be placed against the body of the wearer, while the front section 5 is left temporarily on the outside away from the body of the wearer. The fastening means 21, 22 are then manipulated at the waistline of the wearer, so that the gore 8 will be caused to 15 overlap the gore 7 a considerable distance thereby wrapping the gores around and snugly to the figure of the wearer. After the gores 7, 8 have been secured together the free section 5 of the yoke may be turned over the 20 upper edges of the gores 7, 8 and tucked down between the body of the wearer and the gores.

From the foregoing it will be seen that, 25 when the yoke is used in the long and flowing form of skirt, the garment will be wrapped around the figure of the wearer, so that the yoke sections will snugly embrace the waist, while the top of the skirt gores 30 will slightly overlap and conform to the hips and hang loosely therefrom.

In the short, substantially tight form of skirt, the upper edge of the skirt gores snugly embrace the waist and hips with the front 35 gores overlapped, while the yoke sections lay smoothly between the body and gores.

It will be understood that the peripheral edges of the various parts are hemmed and the seams finished in a manner well-known 40 in the art of dress-making, so that the skirt will present a neat and attractive appearance.

Furthermore, the skirt is simple, economical to manufacture and easily and readily changed from one style to the other.

45 It is obvious that various changes may be resorted to in the form, construction and arrangement of the several parts without departing from the spirit and scope of my invention; and hence, I do not intend to be 50 limited to the details herein shown and described, except as they may be included in the claims.

What I claim is:

1. A wrap-around skirt adjustable to different lengths and widths on the wearer, said skirt comprising an undivided skirt portion and a foldable yoke divided vertically into sections, each section being secured at its bottom to the top of the skirt portion, said skirt portion having means at its top for securing the skirt around the waist of the wearer when the skirt is to be worn short and around the hips of the wearer when the skirt is to be worn long, and certain of said yoke sections having means at their top edges

for securing the skirt around the waist of the wearer when the skirt is to be worn long.

2. A wrap-around skirt adjustable to different lengths and widths on the wearer, said skirt comprising an undivided skirt portion 70 and a foldable yoke divided vertically into sections, each section being secured at its bottom to the top of the skirt portion, said skirt portion having means equally spaced apart along its top for adjustably securing 75 the skirt around the waist of the wearer when the skirt is to be worn short and around the hips of the wearer when the skirt is to be worn long, and certain of said yoke sections 80 having means uniformly disposed along their top edges for adjustably securing the skirt around the waist of the wearer when the skirt is to be worn long.

3. A wrap-around skirt adjustable to different lengths and widths on the wearer, said 85 skirt comprising an undivided skirt portion and a foldable yoke divided vertically into sections, each section being secured at its bottom to the top of the skirt portion, said skirt 90 portion having means at its top for securing the skirt around the waist of the wearer when the skirt is to be worn short and around the hips of the wearer when the skirt is to be worn long, certain of said yoke sections 95 having coacting means at their top edges for securing the skirt around the waist of the wearer when the skirt is to be worn long, and means for removably securing the adjacent vertical sides of the yoke sections together.

4. A wrap-round skirt adjustable to different lengths and width on the wearer, said skirt comprising an undivided skirt portion and a foldable yoke divided vertically into sections, each section being secured at its bottom to the top of the skirt portion, said skirt 105 portion having means along its top for adjustably securing the skirt around the waist of the wearer when the skirt is to be worn short and around the hips of the wearer when the skirt is to be worn long, certain 110 said of yoke sections having coacting means uniformly disposed along their top edges for adjustably securing the skirt around the waist of the wearer when the skirt is to be worn long, and means for removably securing the adjacent vertical sides of the yoke 115 sections together.

5. A wrap-around skirt adjustable to different lengths and widths, said skirt comprising an undivided skirt portion having a back and two front gores and a divided foldable yoke comprising back and front sections secured to the upper edges of said back and front gores of the skirt portion, the top 120 of said skirt portion having means for securing the skirt around the waist of the wearer when the skirt is to be worn short and around the hips of the wearer when the skirt is to be worn long, and the top of said divided yoke having means for securing the skirt 125

around the waist of the wearer when the skirt is to be worn long.

6. A wrap-around skirt adjustable to different lengths and widths, said skirt comprising an undivided skirt portion having a back and two front gores and a divided foldable yoke comprising back and front sections secured to the upper edges of said back and front gores of the skirt portion, the top of said skirt portion having means for adjustably securing the skirt around the waist of the wearer when the skirt is to be worn short and around the hips of the wearer when the skirt is to be worn long, and the top of said divided yoke having means for adjustably securing the skirt around the waist of the wearer when the skirt is to be worn long.

7. A wrap-around skirt adjustable to different lengths and widths, said skirt comprising an undivided skirt portion having a back and two front gores and a divided foldable yoke comprising back and front sections secured to the upper edges of said back and front gores of the skirt portion, the top of said skirt portion having means for securing the skirt around the waist of the wearer when the skirt is to be worn short and around the hips of the wearer when the skirt is to be worn long, the top of said divided yoke having means for securing the skirt around the waist of the wearer when the skirt is to be worn long, and means for removably securing the adjacent sides of the yoke sections together.

8. A wrap-around skirt adjustable to different lengths and widths, said skirt comprising an undivided skirt portion having a back and two front gores and a divided foldable yoke comprising back and front sections secured to the upper edges of said back and front gores of the skirt portion, the top of said skirt portion having means for adjustably securing the skirt around the waist of the wearer when the skirt is to be worn short and around the hips of the wearer when the skirt is to be worn long, the top of said divided yoke having means for adjustably securing the skirt around the waist of the wearer when the skirt is to be worn long, and means for removably securing the adjacent sides of the yoke sections together.

9. A wrap-around skirt adjustable to different lengths and widths, said skirt comprising an undivided skirt portion and a foldable yoke divided vertically into sections, each section being secured to the top of the skirt portion, said skirt portion having means at its top for securing the skirt around the waist of the wearer when the skirt is to be worn short and around the hips of the wearer when the skirt is to be worn long, and the outer sections of said divided yoke having coacting means for securing the skirt around the waist of the wearer when the skirt is to be worn long.

10. A wrap-around skirt adjustable to different lengths and widths, said skirt comprising an undivided skirt portion and a foldable yoke divided vertically into sections, each section being secured to the top of the skirt portion, said skirt portion having means along its top for adjustably securing the skirt around the waist of the wearer when the skirt is to be worn short and around the hips of the wearer when the skirt is to be worn long, and the outer sections of said divided yoke having coacting means for adjustably securing the skirt around the waist of the wearer when the skirt is to be worn long.

In testimony that I claim the foregoing as my invention, I have signed my name this 25th day of May, 1931.

MARIAN RAY.
